United States Patent Office.

J. A. HALL, OF GREENFIELD, INDIANA.

Letters Patent No. 65,074, dated May 28, 1867.

GRAIN-CLEANER.

The Schedule referred to in these Letters Patent and making part of the same.

TO ALL WHOM IT MAY CONCERN:

Be it known that I, J. A. HALL, of Greenfield, in the county of Hancock, and the State of Indiana, have invented a new and useful improved Grain-Cleaner; and I do hereby declare the following to be a full, clear, and exact description of the same, reference being had to the accompanying drawings, making part of this specification, and in which—

Similar letters indicate corresponding parts.

Figure 1 is a vertical longitudinal section.

Figure 2 is a vertical transverse section.

Figure 3 is an elevation of the discharge end of the revolving screen.

The screen revolves on a horizontal axis. A circular series of cams on the head of the screen gives a saltatory motion to the hopper and sieves above through which the grain first passes. A registering shutter on the discharge end of the screen opens and closes the eduction openings.

In the drawings, A is a hopper, and B B are two sieves on the shaking-box C, which is hinged in the standards D D, and has an up-and-down motion given to it by the contact of the cams E E with the projection F on the under side of the shaking-box. The screen G has two heads and a wire-cloth covering, and rotates on a horizontal axis, H, by power applied to the crank I. It receives grain from the spout J after it has passed through the two sieves B B, where the larger offal is removed and falls from the openings b b. The grain from the spout J falls on to the plate K which discharges it into the revolving screen through the opening in the head of the screen. As the rotation of the screen continually brings the grain against a new portion of the wire screen, the finer offal falls through the meshes and is received in and discharged from the hopper L. The clean grain is discharged at the openings M M, at the opposite end of the screen from that at which it was received, and falls into the spout N which conducts it out of the machine. If it be desired to keep the grain in the screen for awhile to remove every trace of offal, the shutter P is rotated so as to shut the openings M. The head g of the screen and the shutter P have openings through them of the same size, which permit the grain to pass when they register, as in fig. 1, but when the shutter is rotated, as in red lines, fig. 3, the passage of the grain is blocked, and it may be retained in the screen as long as desired. The spring R, by engagement with holes in the head g, retains the shutter in the position desired.

Having thus described my invention, what I claim therein as new, and desire to secure by Letters Patent, is—

1. The shaking-shoe C, hinged to the frame, and agitated by contact with the circular series of cams or projections on the head of the rotating screen, substantially as described.

2. The rotating screen G, in combination with the shaking-shoe C, and the shutter P for regulating the discharge, substantially as described.

To the above specification of my invention I have signed my hand this 20th day of March, 1867.

J. A. HALL.
